UNITED STATES PATENT OFFICE

163,094

UTILITY CART

Roger Connor, Athens, Ohio, assignor to The
McBee Company, Athens, Ohio, a corporation

Application December 21, 1948, Serial No. 150,298

Term of patent 14 years

(Cl. D14—3)

To all whom it may concern:

Be it known that I, Roger Connor, a citizen of the United States, residing at Athens, county of Athens, State of Ohio, have invented a new, original, and ornamental design for Utility Cart, of which the following is a specification, reference being had to the accompanying drawing, forming part thereof.

The figure is a perspective view of a utility cart, showing my new design.

I claim:

The ornamental design for a utility cart, substantially as shown.

ROGER CONNOR.
